UNITED STATES PATENT OFFICE.

ANDREW S. OUTCALT, OF IRONTON, WISCONSIN.

RUNNING-GEAR FOR WAGONS AND AUTOMOBILES.

1,352,141.

Specification of Letters Patent.

Patented Sept. 7, 1920.

Application filed October 8, 1919. Serial No. 329,261.

To all whom it may concern:

Be it known that I, ANDREW S. OUTCALT, a citizen of the United States, residing at Ironton, in the county of Sauk and State 5 of Wisconsin, have invented certain new and useful Improvements in Running-Gears for Wagons and Automobiles, of which the following is a specification, reference being had therein to the accompanying drawings.

This invention relates to a running gear for wagons and automobiles and the object of the invention is the improvement of the construction of a running gear which will 15 make it possible to turn a wagon in a short or small space, and which gear will remove the strain or jar off the horses when the wheels are passing over rough or uneven ground.

With this and other objects in view, my invention comprises certain novel constructions, combinations and arrangements of parts as will be hereinafter fully described, illustrated in the accompanying drawings 25 and more particularly pointed out in the appended claims.

In the drawings:

Figure 1 is a plan view of a running gear constructed in accordance with the present 30 invention.

Fig. 2 is a perspective view of a portion of one of the axles and one of the bearing plates.

Fig. 3 is a view in end elevation of the 35 running gear.

Fig. 4 is a fragmentary perspective view of the running gear, showing particularly one end thereof.

Fig. 5 is a sectional view taken on line 40 5-5, Fig. 4.

Referring to the drawings by numerals, 1 designates the axles upon the ends of which are journaled the wheels 2. The hound frames 3 are positioned above the 45 axles and between the frames is the coupling pole 4.

Each hound frame comprises curved end portions 5 integral at their ends with inwardly-extending central portions 6 and 7. 50 The rear central portions 7 are bent at 8 to form parallel vertical portions 9 and 10. The outer end of portion 9 terminates in an overlapping horizontal portion 11 that rests upon the coupling pole 4 (Figs. 55 1 and 4). Between the parallel portions 9 and 10 are bracing and filling pieces. Bolts

13 extend into these filling pieces 12 fastening the flat portion 11 securely thereto. It is to be understood that both ends of my running gear are similarly constructed and hence it is only necessary to specifically describe one end. Further, the tongue can be attached to either end and I make no claim for the tongue attachment, not shown. It is also to be understood that if the wagon 65 should be mired, the tongue or drawing means can be removed from one end and attached to the other end and thereby, in many cases, quickly remove the wagon from its mired condition.

On each hound frame, and attached to the outer ends of the filling pieces 12 is a bolster 14, and resting upon the bolsters is the box 15 (Fig. 3).

Each axle is pivotally connected to the 75 bolster and the hound frame by means of a vertical bolt 16; each axle is free to rotate, and to cause the axles to move in unison I place two bearing plates 17 upon each axle under the outer curved portions 80 5 of the hound frame. Each bearing plate makes the structure more durable and very efficient for the plate rests upon the top of the axle and centrally of the plate is an integral depending lug 18 that fits in an 85 elongated pocket 19 of the axle (Fig. 2) and in the lug is a threaded aperture 20 that registers with aperture 21 in the axle. Curved parallel ears 22 are formed at one end of the plate and between these ears is slidably positioned the curved end 5 of the hound frame. In the plate and between the ears 22 is a roller bearing 23 upon which the curved end 5 of the hound frame bears or travels making an easy sliding connection 90 95 greatly facilitating the turning of the axles.

Extending into the aperture 21 are threaded draw bolts 24; each draw bolt is provided with an outer hooked end 25 to 100 which end is attached a chain 26; there are two chains used in my running gear, crossing each other, so that when the axle that may be used as a front axle is turned in one direction, proper turning of the other 105 or rear axle will be caused, to turn the wagon in a short space; furthermore, these chains prevent the axles from wabbling or unduly swinging, relieving considerable strain off the horses.

Each draw bolt 24 is threaded into the aperture 20 of the lug 18, and this keeps

the draw bolt in position upon the axle, and at the same time locks the bearing plate 17 upon the axle under the hound frame; the apertured lug performs two functions, 5 to wit: the anchoring means for the bearing plate and the receiving means for the draw bolt.

In the foregoing description I have described the preferred form of my invention, 10 but in the manufacture of the same on a large scale, certain minor alterations or changes may be found desirable by one skilled in the art to which this invention relates and, therefore, I reserve the right to 15 make such minor alterations or changes as shall fairly fall within the scope of the appended claims.

What I claim is:

1. In a running gear, the combination of 20 a pair of axles, hound frames resting upon said axles, each hound frame provided with outer end portions and with inwardly extending central portions, some of said central portions being bent at their inner ends 25 and producing parallel portions, one of said parallel portions having an integral flat portion, filling pieces between said parallel portions and under said flat portion, means fastening said flat and parallel portions to said 30 filling pieces, a bolster resting upon each hound frame and against the outer ends of the filling pieces, and a coupling pole positioned between the filling pieces and the parallel portions of the hound frames.
- 35 2. In a running gear, the combination of axles, each axle provided with a pair of elongated pockets formed in its upper face and with transverse apertures intersecting said pockets, bearing plates resting upon 40 each axle, each bearing plate provided with a depending lug extending into the pocket of each axle, said lug provided with a threaded aperture registering with the intersecting aperture of the axle, each bearing 45 plate provided at one end with concentric

curved upwardly extending ears, a roller bearing upon said plate between said ears, hound frames having portions resting between the ears upon said roller bearings, draw bolts having threaded ends extending 50 into the intersecting apertures of the axles and into the threaded apertures of the lugs, and crossed chains mounted upon the outer ends of the draw bolts.

3. In a running gear, the combination of 55 a pair of axles, bearing plates resting upon said axles, each bearing plate provided with a depending lug extending into the axle, hound frames resting upon said bearing plates, bolsters resting upon said hound frames, a coupling pole connected to said bolsters, draw bolts extending into said axles and into said depending lugs of the bearing plates, and flexible connecting 60 means attached to the outer ends of the 65 draw bolts.

4. In a running gear, the combination of 70 a pair of axles, a pair of bearing plates resting upon said axles, each bearing plate provided with a central depending lug and 75 with a pair of parallel upwardly extending ears at one end, said axles provided with apertures extending therethrough, said lug of each bearing plate provided with a threaded aperture registering with an aperture of the axle, and draw bolts having inner threaded ends extending into the apertures of the axles and through the threaded 80 apertures of the lugs, each draw bolt provided with an outer hooked end, chains 85 mounted upon the hooked ends of said draw bolts, hounds resting upon said bearing plates and having portions positioned between the ears of each plate, a coupling pole connected to said hounds, and bolsters resting 85 upon the hounds.

In testimony whereof I hereunto affix my signature.

ANDREW S. OUTCALT.
